(57) **CLAIM**

The ornamental design for a bill payer's desk, as shown and described.

DESCRIPTION

FIG. 1 is a front perspective view showing the desk in a closed position.

FIG. 2 is a front perspective view showing the desk with the horizontal writing surface extended; and,

FIG. 3 is a rear perspective view showing the desk with the horizontal writing surface extended.

The desk in which the design is embodied is intended to provide easily accessible file drawers, a writing surface, a magazine bin, storage accommodations and a letter carrier.

1 Claim, 3 Drawing Sheets

FIG. 1

FIG. 2

FIG. 3
